UNITED STATES PATENT OFFICE.

GUSTAV J. SENGBUSCH, OF MILWAUKEE, WISCONSIN.

INK-WELL.

1,109,019.

Specification of Letters Patent. Patented Sept. 1, 1914.

Application filed November 29, 1912, Serial No. 733,934. Renewed November 7, 1913. Serial No. 799,815.

To all whom it may concern:

Be it known that I, GUSTAV J. SENGBUSCH, a resident of Milwaukee, in the county of Milwaukee and State of Wisconsin, have invented certain new and useful Improvements in Ink-Well, of which the following is a specification.

My invention relates to ink wells, particularly to automatically sealed ink wells, and may be considered as an improvement over the ink well disclosed in my Patent No. 841,345, issued January 15, 1907.

In the above patent, the fountain chamber is of hard rubber and extends entirely to the bottom of the ink bowl, and at its bottom is provided with valve mechanism for admitting in-flow of ink from the bowl. In order to accommodate the large fountain chamber in which the plunger plays, the bottom of the ink bowl must be of sufficiently large diameter and the cost of the ink well is therefore considerable.

Among the important objects of my invention are to eliminate the entire lower part of the fountain structure to leave only a guide neck for the plunger stem, and a flange surrounding the lower end of this neck for engaging with an annular seat provided on the bowl, such construction enabling reduction of diameter of the lower part of the bowl and consequent saving in material; to make the intermediate cover and plunger guide neck structure of glass and to grind the outer edge of the flange and the bowl seat with which it engages so that accurate and tight fitting will result and the lower portion in which the plunger piston plays will be sealed from the upper portion of the bowl surrounding the plunger stem guide neck; to provide an improved arrangement for permitting overflow at the top of the guide neck and from the dip recess; and in general to provide arrangement and construction which will eliminate as much as possible expensive rubber construction and valve mechanism and which will effect saving in material so that the ink well may be constructed for less cost and therefore be better adaptable for more general usage, as for example in schools, the above improved construction better fitting the ink well for insertion in pockets in school desks.

The various features of my invention are clearly illustrated in the accompanying drawings in which—

Figure 1 is a diametral vertical sectional

view, Fig. 2 is a plan view thereof with the cover structure removed, Fig. 3 is a vertical sectional view taken on a diametral plane at right angles to that of Fig. 1 and showing the ink well being used, Fig. 4 is a perspective view of the structure having an intermediate cover and plunger guide neck, and Fig. 5 is a view of the bottom side of the main cover structure with the dipping guide head in place.

The bowl 10 of the well is of cylindric form whose side wall has an annular outward offset 11, above which offset is a reservoir chamber 12 and below which offset is a plunger chamber 13. The bowl is preferably of glass and the inner surface thereof just below the offset 11 is ground to form a seat 14 for the plunger guiding structure designated as a whole 15. This structure 75 comprises the cylindrical neck portion 16 from whose lower edge extends the flange 17 for forming an intermediate cover or partition between the chambers 12 and 13. The structure 15 is preferably of glass and the outer edge of the flange 17 is ground to accurately fit with the ground seat 14 on the bowl. One or more narrow slots or passageways 18 are provided through the flange, preferably at the edge thereof, for allowing flow between the upper and lower chambers to equalize the levels of the ink therein. Slidable freely in the neck 16 is a stem 19 extending upwardly from the plunger 20, the stem and plunger being hollow and sealed so that it will readily float in the ink in the lower chamber 13. To enable ink to flow upwardly upon depression of the plunger structure, longitudinal grooves 21 are provided in the neck 16 and the combined areas of these by-passes is greatly in excess of the combined area of the slots 18 so that upon depression of the plunger structure, the greater part of the ink will flow upwardly through the neck by-passes, the slots 18 being merely for the purpose of allowing gradual restoration to level after a quantity of ink has been forced upwardly through the neck and into the upper chamber 12, such flow of ink to the chamber 12 taking place over the top of the neck 16.

The main cover structure is preferably of metal and in the form of a circular disk 22 having an annular depending flange 23 near its periphery and threaded to engage with the threaded upper end of the bowl, a gasket 24 being preferably inserted between

- the cover and the bowl edge to effect perfect seating at this point. At its center the cover has a circular passageway 25 into which tightly fits the annular flange 26 of 5 the dipping guide head 27, this head being annular and of cone shape cross section and surrounding the dip opening 28 registering with the neck 16. The dip head flange 26 receives the upper end of the neck when the 10 cover structure is applied to the bowl but the upper end of the neck, although extending a distance into the flange 26, terminates short of the base of the dip head, and in the flange 26 passageways 29 are provided 15 through which may flow ink forced up through the passageways 21 by the plunger, and through which air is admitted to compensate for withdrawal of ink from the bowl.
- 20 When the ink well is filled and is not being used, the plunger structure will be floated and held with the upper face of its stem tightly against the base of the head 27 to close the dip opening 28, it being noted 25 that the edge about the opening 28 overhangs the passageways 21 so that upon sudden depression of the plunger structure and consequent rapid rush of ink through the passageways, the ink will not spurt out 30 through the dip opening but will strike against the overhanging head and will be deflected radially, most of it being deflected radially inwardly over the top end of the plunger stem to be received by the pen, some 35 of the ink flowing directly back to chamber 12 through the passageways 29 in the dip head flange 26. When the plunger structure is released it will be returned to its upper position by the pressure of the ink. Some of 40 the ink will flow back into the lower chamber 13 down the grooves 21 and the remainder of the ink will flow back to the upper chamber 12 through the passageways 29 and then the level in the two chambers 45 will gradually equalize through the passageways 18. These passageways being vertical will not clog as there is no chance for particles to lodge therein or at the openings thereof. If such passageways were horizontal 50 they would readily clog and destroy the operativeness of the well. As the ink becomes used up and is no longer able to float the plunger structure, the plunger structure will rest on the bottom of the ink well and 55 in order to prevent sticking of the plunger structure when the ink well is again filled, its bottom is made slightly convex and on the floor of the well a peak 30 is provided for receiving the apex of the bottom of the 60 float structure. A space is thus left between the plunger structure and the bowl bottom for the accumulation of sediment or thickened ink and the practically one point engagement of the plunger structure with the 65 peak will offer no resistance to immediate

floating of the plunger structure when the ink well is refilled, or when the plunger is released after being completely depressed by a pen.

The flange 17 of the intermediate structure may be more or less skeletonized to lessen the material and to make the structure lighter. As shown in Fig. 4, the flange is hollowed out but guide projections 31 may be left for the plunger head 20 in order to hold the plunger stem centrally in the neck 16 and prevent sticking thereof. The entire ink well is therefore constructed with a minimum number of parts each of which has a minimum amount of material, so that the structure is very light, and by the direct engagement of the intermediate structure with the bowl wall the diameter of the well can be greatly reduced. The intermediate structure being of glass will not warp as 85 rubber would be apt to do, and with the ground engaging surfaces, this intermediate structure has accurate and secure seating in the bowl to hold the neck part thereof in vertical alinement so that the float stem may 90 freely reciprocate therein. All valve mechanism being eliminated, there are no small parts which might readily become displaced or lost or which might stick to other parts and refuse to operate. When the ink well is 95 sufficiently filled to keep the float up against the dip guide head, the well is entirely sealed and the ink will be kept in proper fluid condition and free from dust, etc.

The ink well is particularly adaptable for 100 use in schools as it can readily be supported in a pocket in a desk top. As shown in Figs. 1 and 3, the ink well is supported by a top 32 in a pocket 33 provided therein, the outer side of the offset part 11 seating 105 against the annular ledge 34.

Changes and modifications may be made which would incorporate the features of the invention and I do not desire to be limited to the precise construction and arrangement 110 shown and described and

I claim the following:

1. In an ink well structure, the combination of a bowl, a cover for said bowl having a depending annular flange, a guide member adapted to seat at its lower end against the inner wall of said bowl and having its upper end extending into said flange, said guide member having a central vertical passageway therethrough, a float member adapted to play in said passageway, an abutment on said cover for said float member and a dip opening through said abutment, said guide member having passageway therethrough through which ink may 120 flow upon depression of said float member, the upper end of said guide member terminating short of said abutment and said flange having overflow passageways.

2. In an ink well structure, the combina- 130

tion of a bowl, a cover structure for said bowl having a depending annular flange, an intermediate partition seating against the inner face of said bowl and having an upward extension received by said annular flange, said intermediate wall and extension dividing said bowl into an upper and lower chamber, said extension having a vertical guide passageway, a float member in said lower chamber having a stem engaging in said passageway, an abutment on said cover structure for the upper end of said stem and a dip opening through said abutment to said stem, said extension having bypasses through which ink may flow upon depression of the stem and displacement of ink in the lower chamber, over-flow passageways in said cover flange whereby ink may flow from the top of the stem to the upper chamber, and level equalizing passageways through said intermediate wall.

3. In an ink well structure, the combination of a bowl, a cover structure for said bowl having a depending annular flange, an intermediate partition seating against the inner face of said bowl and having an upward extension received by said annular flange, said intermediate wall and extension dividing said bowl into an upper and a lower chamber, said extension having a vertical guide passageway, a float member in said lower chamber having a stem engaging in said passageway, an abutment on said cover structure for the upper end of said stem and a dip opening through said abutment to said stem, said extension having bypasses through which ink may flow upon depression of the stem and displacement of ink in the lower chamber, over-flow passageways in said cover flange whereby ink may flow from the top of the stem to the upper chamber, and level equalizing passageways through said intermediate wall, said bowl and intermediate wall and extension being of glass and the seat and engaging surfaces being ground.

4. In an ink well structure, the combination of a bowl, a metallic cover for said bowl having a central opening, a dipping guide head having a flange extending through said opening, an intermediate structure seating against the sides of said bowl intermediate its ends and having an upward extension received by the lower end of said flange, a float member in said bowl having a neck extending through said extension, said extension having bypasses through which ink may flow upon depre-

sion of the float member, said flange having overflow passageways through which ink may flow from the top of said float and the upper end of said extension.

5. In an ink well structure, the combination of a bowl, a cover for said bowl having a dip opening, a flange depending from said cover and surrounding said opening, a guide frame in said bowl having its upper end extending into said flange, said guide frame having a vertical passageway therethrough, a float member adapted to play in said passageway and to be floated by ink in the well to hold its upper surface against the under side of the cover to seal the dip opening, said guide frame having passageway therethrough through which ink may flow upon depression of said float member, and over-flow passageway for the flow of ink back to the well from the space in the guide frame above the depressed float member.

6. In an ink well structure, the combination of a bowl, a cover for said bowl having a dip opening, a flange depending from said cover and surrounding said opening, a guide frame in said bowl having its upper end extending into said flange, said guide frame having a vertical passageway therethrough, a float member adapted to play in said passageway and to be floated by ink in the well to hold its upper surface against the under side of the cover to seal the dip opening, said guide frame having passageway therethrough through which ink may flow upon depression of said float member, the upper end of said guide frame terminating short of the cover, and said flange having over-flow passageways therethrough.

7. In an ink well structure, the combination of a bowl, a cover for said bowl having a dip opening, a guide frame in said bowl cooperating with the bowl to form a float compartment, a float member in said compartment extending upwardly through the frame to abut against the cover to close the dip opening, said frame having passageway therethrough for the flow of ink upwardly into the space above the depressed float member, and vertical equalizing passageways between said float compartment and the space at the outside thereof.

In witness whereof, I have hereunto subscribed my name, this 26th day of November, A. D., 1912.

GUSTAV J. SENGBUSCH.
